(57) **CLAIM**

The ornamental design for a laptop computer, as shown and described.

DESCRIPTION

1.-3. Laptop computer

1.1: Front in a closed state

1.2: Back in a closed state

1.3: Left in a closed state

1.4: Right in a closed state

1.5: Top in a closed state

1.6: Bottom in a closed state

1.7: Top, Left, Front Perspective in a closed state

1.8: Top, Back, Right Perspective in a closed state

1.9: Top, Back, Left Perspective in an open state

2.1: Front in a closed state

2.2: Back in a closed state

2.3: Left in a closed state

2.4: Right in a closed state

2.5: Top in a closed state

2.6: Bottom in a closed state

2.7: Top, Left, Front Perspective in a closed state

2.8: Top, Back, Right Perspective in a closed state

2.9: Top, Back, Left Perspective in an open state

3.1: Front in a closed state

3.2: Back in a closed state

3.3: Left in a closed state

3.4: Right in a closed state

3.5: Top in a closed state

3.6: Bottom in a closed state

3.7: Top, Left, Front Perspective in a closed state

3.8: Top, Back, Right Perspective in a closed state

3.9: Top, Back, Left Perspective in an open state

(Continued)

The broken lines shown in the drawings illustrate portions of the laptop computer that form no part of the claimed design.
